UNITED STATES PATENT OFFICE.

CATHERINE THERESE McLAUGHLIN, OF NEW YORK, N. Y.

ATTACHMENT FOR GAS-BURNERS.

1,320,075.

Specification of Letters Patent.

Patented Oct. 28, 1919.

Application filed February 26, 1919. Serial No. 279,254.

To all whom it may concern:

Be it known that I, CATHERINE T. McLAUGHLIN, a citizen of the United States, residing at New York, in the county of New 5 York and State of New York, have invented certain new and useful Improvements in Attachments for Gas-Burners, of which the following is a specification.

This invention relates to an improvement 10 in attachments for gas-stove burners.

To this end the invention contemplates a novel and practical device which will not only cause the proper mixing of gas and air but also effectively distribute the heat generated by the burner, thereby utilizing the 15 caloric efficiency of the burner flame to a maximum degree. That is to say, the invention proposes to provide an attachment which may be readily fitted to an ordinary 20 gas burner to evenly disperse the flame and also assist in causing a more thorough mixing of the air and gas which will insure perfect combustion with the result of increasing the intensity of heat, and at the 25 same time eliminate objectionable and dangerous odors.

With the above and other objects in view which will more readily appear as the 30 nature of the invention is better understood, the same consists in the novel construction, combination and arrangement of parts hereinafter more fully described, illustrated and claimed.

A preferred and practical embodiment of 35 the invention is shown in the accompanying drawing, in which:

Figure 1 is a top plan view of the attachment.

Fig. 2 is a vertical sectional view on the 40 line 2—2 of Fig. 1.

Similar reference characters designate corresponding parts throughout the several figures of the drawing.

In carrying the present invention into effect 45 it is proposed to utilize a flat plate or disk 1 provided with a plurality of openings having a novel relation and arrangement to effect a proper distribution or dispersion of the heat. That is to say, it is proposed 50 to provide the metal burner-plate or disk 1 with a plurality of openings 2 which may be conveniently arranged in a plurality of series of circles bearing concentric relation, the said openings of each series gradually increasing in diameter from the cen-

ter of the disk toward the perimeter, as clearly indicated in the drawing.

Accordingly, it will be apparent that one of the novel and distinctive features of the present invention is the provision of a heat distributing burner plate having a plurality of openings or perforations which are of progressively increasing diameter between the axis of the plate and the outer edge thereof. Thus the central portion of the plate 60 contains openings of relatively small diameter while those of the largest diameter are located adjacent the outer edge portion. This structure causes the heating flame to be diverted or dispersed uniformly over 65 the entire surface of the disk, and prevents the concentration of heat at any one point, with the resulting destructive effect on cooking utensils.

By reference to the drawing it will be further observed that it is proposed to mount the heating plate or disk 1 upon suitable supporting blades 3, which are radially disposed with reference to the axis of the disk, and may be of any desired length, say from 70 one to three inches as the requirements of the burner plate demand. Although the blades are shown as beginning a short distance from the center of the plate, they may start closer to the center and at all events 75 are particularly designed and intended to rest upon the usual gas burner B, whereby the plate 1 will be spaced a proper distance 80 above the openings in the burner, and provide in effect a plurality of relatively large 85 mixing chambers for the gas and air, which not only insures proper mixing thereof but also draws considerably more air than gas 90 into the flame after the burner starts.

In addition to serving as supports for the 95 disk the blades serve as baffles to distribute the flame in the space between the disk and the burner to assist the injector action of the burner. That is to say, the special arrangement of the blades 3 is such that they both 100 distribute the flame and support the plate 1 whereby the pressure of gas is increased very materially by the suction that is created by the flame passing through the openings 2 and between the blades. Thus, the 105 operation of the burner insures considerably more air being burned than would be otherwise possible because the heat of the burner plate, and the flame pushing between the blades and through the multiplicity of open- 110

ings will cause a suction whereby a relatively great volume of air will be drawn in from the free and unobstructed sides of the plate to be used in increasing the intensity of the flame.

From the foregoing it will be apparent that the present invention provides an attachment including a perforate burner plate which not only uniformly distributes the heat from the usual gas burner, but also provides a more intense heating flame by reason of the fact that the pressure created by the flame-jets issuing from the usual burner is materially increased by the passage of the flame between the blades and through the multiplicity of openings in the burner plate. In other words the tongues of flame being projected through the openings have an injector effect which causes a much greater heating efficiency from a smaller quantity of gas because a preponderant amount of air is utilized in forming the proper mixture for the flame.

Another novel and distinctive feature of the invention is that of providing the center of the plate with small openings where the flame is likely to be the hottest, while the

outer portions of the plate are provided with larger openings to equalize the heating effect of the flame.

Without further description it is thought that the features and advantages of the present invention will be readily apparent.

I claim:—

An attachment for gas burners comprising in combination with the burner, a burner plate having a plurality of graduated openings therein for uniformly dispersing the flame of the burner, and blades carried by the underside of the perforate plate for supporting the same above the gas burner, to provide a relatively capacious mixing chamber having an unobstructed air intake area entirely around the perimeter of the plate, whereby the flame issuing from the burner will have an injector effect in passing through the openings of the plate, to draw air from the sides of the plate.

In testimony whereof I hereunto affix my signature in the presence of two witnesses.

CATHERINE THERESA McLAUGHLIN.
